UNITED STATES PATENT OFFICE.

WALTER N. MECKLAN, OF OLEAN, NEW YORK.

LOCK-NUT.

SPECIFICATION forming part of Letters Patent No. 686,318, dated November 12, 1901.

Application filed March 11, 1901. Serial No. 50,701. (No model.)

To all whom it may concern:

Be it known that I, WALTER N. MECKLAN, a citizen of the United States, residing at Olean, in the county of Cattaraugus and State of New York, have invented certain new and useful Improvements in Lock-Nuts; and I do hereby declare the following to be a full, clear, and exact description of the invention, such as will enable others skilled in the art to which it applies to make and use the same.

This invention relates to nut-locks, and has for its object to provide an improved pawl-and-ratchet arrangement for interlocking the nut against accidental unscrewing from the bolt and at the same time arranged for convenient disengagement to permit of the ready removal of the nut. It is furthermore designed to have the locking means housed by the nut and also arranged so as not to be interfered with by a wrench applied to the nut.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a sectional view illustrating a bolt and nut equipped with the present invention. Fig. 2 is a transverse sectional view thereof. Fig. 3 is a detail view of a key for releasing the locking means.

Like characters of reference designate corresponding parts in all of the figures of the drawings.

To illustrate the present invention, there has been shown an ordinary bolt 1, having the usual nut 2, which is screwed up tight against the part 3, through which the bolt is passed. In carrying out the invention one corner of the nut is notched. Preferably the outer portion thereof is cut off, as indicated at 4, and at this point a radial opening or perforation 5 is formed through one side of the nut and communicates at its inner end with the bolt-opening thereof. At substantially right angles to this perforation another perforation or opening 6 is formed from the

back of the nut forwardly and communicates with the middle portion of the former perforation. Within the radial opening there is 55 slidably mounted an endwise-movable ratchet pawl or dog 7, which has an enlarged head 8 upon the outer end thereof to lie against the bottom of the notch or recess in the adjacent corner of the nut, and thereby limit the inward movement of the pawl. The inner end of the pawl is beveled transversely, as at 9, and in the opposite side of the pawl there is provided a notch which produces a sharp spur or tooth 10 between the notch and the 60 beveled face 9, so that the nut may be turned to the right, as the beveled face 9 will slide over the threads; but an opposite turning of the nut will bite the pointed spur or tooth into the threaded portion of the bolt, thereby 65 locking the nut against being unscrewed. To prevent outward displacement of the pawl and also place an elastically-yieldable tension thereon for the purpose of normally holding the inner end of the pawl against the 70 threaded portion of the bolt, there is provided a folded substantially U-shaped spring 11, which has one end portion inserted inwardly into the opening 6, so that the extremity of its inner side may lie in a notch or recess 12 75 in the adjacent side of the pawl, the opposite free extremity of the spring being bent inwardly into a coil or spring loop 13, lying between the opposite sides or members of the spring, so as to place an additional tension 80 upon the end which is in engagement with the pawl. Thus the pawl can yield outwardly when screwing the nut to place and is normally held in engagement with the bolt.

It will be observed that when the nut is 85 set up against a surface the latter closes the outer end of the opening in which the spring is mounted, so as to prevent loss thereof. Moreover, the outer end of the spring lies at the outer end of the opening, and the part 3, 90 through which the bolt passes, forms a stop in engagement with the spring, so as to prevent the latter from being jarred out of engagement with the pawl. By having the head of the pawl seated in a notch or recess 95 it lies within the outer marginal edge of the nut and therefore does not interfere with the application of a wrench to the nut, nor is the pawl interfered with by the wrench, as there

is sufficient space between the head of the pawl and the outer margin of the nut to permit of the necessary play of the pawl in screwing the nut upon the bolt.

5 To unscrew the nut, it is first necessary to disengage the pawl from the bolt, and this may be readily accomplished by inserting a bifurcated tool or implement 14 between the head of the pawl and the back of the recess

10 4 to draw the pawl outwardly from engagement with the bolt, whereby the nut is freed and may be unscrewed. While it is preferred to use the bifurcated tool, any pointed or bladed implement—as, for instance, a knife—
15 may be inserted beneath the head of the pawl to withdraw the same.

What is claimed is—

1. A nut having a perforation formed therein and communicating with the bolt-opening, 20 and also provided with a perforation formed through the back of the nut and communicating with the former perforation, an endwise-slidable bolt-engaging pawl mounted in said former perforation and a pawl-engaging 25 spring mounted within the other perforation, the outer end of the latter opening being the only exposed portion thereof and said end being closed by the part against which the nut may be set.

30 2. A nut, having a transverse opening intersecting the bolt-opening, and a perforation formed through the back of the nut in substantially the direction of the bolt-opening

and communicating with the transverse opening, an endwise-slidable pawl mounted in the 35 opening, and a folded spring having its free end portions inserted inwardly through the outer end of the perforation and housed entirely within the perforation, the sides of the 40 spring being in frictional engagement with the walls of the perforation, the terminal of the inner side being in engagement with the pawl, and the outer bent end of the spring being at the outer open end of the perforation.

3. A nut, having a socket or recess formed 45 in the outer marginal edge thereof and intersecting the front of the nut, there being a transverse opening extending through the back of the socket and communicating with the bolt-opening, and also a perforation 50 formed through the back of the nut and in communication with the transverse opening, an endwise-slidable pawl mounted in the opening, with its inner end provided with a laterally-inclined bolt-engaging tooth, and an 55 outer terminally-enlarged head to limit the inward movement of the pawl, and a spring housed within the perforation and connected to the pawl to force the latter inwardly.

In testimony whereof I affix my signature 60 in the presence of two witnesses.

WALTER N. MECKLAN.
